ROTARY FRICTION ASSEMBLY

Joseph Geczy, Maplewood, N. J., assignor to The
S. S. White Dental Manufacturing Company, a
corporation of Pennsylvania

Application April 8, 1944, Serial No. 530,142

6 Claims. (Cl. 188—80)

My invention relates particularly to mechanism embodying means for carrying spools or reels from which strands may be drawn to be fabricated into a flexible shaft, cable, woven fabrics or other fabricated article of manufacture and is particularly directed to the means for rotatably supporting said spools.

In mechanism of the class contemplated, it has been customary to control the tension of strand payout spools or reels by means comprising adjustable spring loading devices which include sliding friction between suitably supported cork or other friction material and a steel disk or plate. In such devices, the running and starting friction between the relatively moving parts differs materially and consequently tends to vary the tension on the strands being drawn from said spool or reel. This variation in tension of the strands is highly detrimental in the fabrication of flexible shaft or cable, as such variation is reflected in the finished product.

The principal objects of my invention are to provide means, embodied in the spool or reel supporting structure, arranged to retard the rotation of the strand dispensing spools, and to afford such uniformity of retardation as to insure that the effective tension necessary to withdraw the strand from the spool shall be substantially constant or uniform.

Other objects of my invention are to provide means whereby the ball bearing units which rotatably support the reel mounting may be utilized to effect the required retarding friction between the relatively rotating members and to produce the desired uniform tension on the strand being withdrawn from the ball bearing supported reel.

My invention includes such an arrangement of the ball bearing units which rotatably support the reel mounting that the inner and outer race-rings may be caused to yieldingly bind with predetermined degrees of pressure to create in the ball bearing units friction between the balls and their ball race surfaces, which tends to retard relative rotation of the opposed inner and outer race-rings.

My invention comprehends a reel mounting carried by a single ball bearing unit having a split ball race-ring in which the opposed annular members may be relatively adjusted to effect pressure between the inner and outer ball race-rings and the interposed series of balls, and having means arranged to vary the space between the opposed members of said split ball race-ring whereby the series of balls are forced to bind against the rela-

tively opposed cooperating ball race-rings of said unit.

The form of my invention as hereinafter more specifically described comprises a ball bearing unit or units suitably mounted upon a shaft or arbor with the inner ball race-ring preferably engaged in non-rotatable relation therewith, and having a spool or reel mounting rotatably carried by said unit or units, said reel mounting being conveniently provided with intersecting longitudinal and transverse grooves with which projections on the inner surface of the reel may securely engage. Said reel mounting may preferably be provided with internally disposed screw threads with which an annular screw flange may be engaged for relative axial adjustment and between which and one of the ball race-rings an annular spring washer is disposed tending to force the inner and outer ball race-rings axially out of their normal plane of alignment, to cause the said ball race-rings to so bind upon the interposed balls and thereby produce friction to retard the relative rotation of the inner and outer ball race-rings.

My invention also includes all of the various novel features of construction and arrangement as hereinafter more definitely specified.

In the accompanying drawings, Figure 1 is a transverse vertical sectional view of a rotary friction assembly including a strand carrying spool or reel mounting and showing a spool or reel mounted thereon in position to pay out the strands wound thereon; Fig. 2 is a vertical longitudinal sectional view of the assembly structure illustrated in Fig. 1, taken on the line 2—2 in said figure; Fig. 3 is a vertical longitudinal sectional view similar to Fig. 2 but embodying a modified form of assembly structure; Fig. 4 is a vertical longitudinal sectional view embodying another modification of the assembly structure; Fig. 5 is a plan view of the reel mounting per se; Fig. 6 is a perspective view of the annular spring washer which is interposed between the axially adjustable screw flange follower and the ball bearing units shown in Fig. 2 to effect pressure tending to produce uniform friction between the opposed ball race-rings and the interposed balls; Fig. 7 is a perspective view of the adjusting nut shown in Fig. 4; and Fig. 8 is a perspective view of the spring washer shown in said Fig. 4.

In said figures, and with particular reference to Figures 1 and 2, the shaft or spindle 1 which is provided with the bore 2 extending therethrough, carries the sleeve 3 upon which two ball bearing units are mounted, one comprising the relatively concentric inner and outer race-rings

5 and 6 respectively and the interposed bearing balls 7, with their attendant spacing ring 8, and the other comprising the inner and outer race-rings 9 and 10 respectively and the interposed bearing balls 11, with their attendant spacing ring 12.

The inner race-rings 5 and 9 are maintained relatively spaced apart by the annular spacing washer 13 and are prevented from axial displacement by the collars 15 and 16 which may be suitably keyed to the shaft 1 as by the set screws 17 and 18 respectively, or by any other convenient means.

The outer race-ring 6 carries the spool or reel mounting 19, which conveniently serves as a housing for the ball bearing units, having its annular inturned end flange 20 provided with the circular recess 21 arranged to clear the lateral face of the inner race-ring 5, as best shown in Fig. 2, and having an internally disposed recess 22 in its cylindrical wall 23 arranged to clear the external cylindrical surface of the outer race-ring 10, so as to permit relative axial movement of said race-ring 10 with respect to the race-rings 5, 6 and 9, and the housing or mounting 19 being limited, however, by the bearing balls 7 and 11 traversing the opposed grooved ball races in said race-rings.

As shown in Fig. 2, the cylindrical wall 23 of the reel mounting 19 is internally threaded adjacent to its open side providing the screw threads 24 with which the adjustable annular closure flange 25 is threadedly engaged to be adjusted axially by means of a suitably provided tool which may engage the slots 26 to effect its rotation.

Said closure flange 25 is provided with a circular pocket 27 in its inner surface arranged to retain the annular spring washer 29 which is preferably frustro-conoidal in form and which yieldingly bears against the outer ball race-ring 10 with pressure tending to force said ball race-ring 10 out of its normal plane of alignment with respect to its complementary cooperative inner ball race-ring 9, thus tending to effect such lateral pressure upon the bearing balls 11 as to produce abnormal rolling friction between said balls and the relatively concentric race-rings 9 and 10 respectively.

Obviously, this yielding pressure is directed by the inner race-ring 9 against the inner race-ring 5 through the spacing washer 13 to force said race-ring 5 out of its plane of alignment with respect to its complementary cooperative outer race-ring 6 which is engaged in and moves axially with the housing or reel mounting 19, thus tending to effect such lateral pressure upon the balls 7 as to produce abnormal friction between said balls and the relatively concentric race-rings 5 and 6 respectively.

The friction thus produced between the bearing balls and their respectively cooperative race-rings may be varied to any predetermined extent by relative axial adjustment by the closure flange 25 and the reel mounting 19, which may be conveniently effected through rotation of said closure flange 25 by means of a suitable tool such as a spanner wrench engaging the slots 26 which extend radially in the outer face of said flange 25.

The hub formed by the assembly thus described may be variously employed, as, for instance, the hub of a wheel or other rotatable mechanism. However, in the present instance it conveniently serves as a mounting for a strand carrying spool or reel.

The mounting 19 has its peripheral wall provided with a series of transverse slots 30, 31, 32 and 33, which are intersected by the circumferential slot 35 whose depth so varies as to afford cam surfaces 36, 37, 38, 39, 40, 41, 42 and 43 respectively having their lowest regions at the intersection of said transverse slots, and their highest regions intermediate of said transverse slots, as shown in Fig. 1.

Said mounting 19 serves as a convenient support for the strand carrying and payout reel 45 whose inner cylindrical wall 46 is provided with the inwardly extending projections 47, 48, 49 and 50 which may be entered into the corresponding transverse slots 30, 31, 32 and 33, so as to permit the reel 45 to be axially slipped over said mounting into proper registry therewith and then rotated with its projections 47, 48, 49 and 50 guided by the circumferential slot 35 until said projections engage the cam surfaces that may be encountered, which, as shown in Fig. 1 are the cam surfaces 36, 38, 40 and 42, whereby said reel may be rigidly held on the hub or mounting but readily withdrawn and replaced.

In the modified form of my invention illustrated in Fig. 3, the shaft or spindle 51, which is provided with the bore 52 extending therethrough, carries the ball bearing unit comprising the inner ball race-ring 55 and the relatively concentric axially spaced outer race-rings 56 and 57, the interposed bearing balls 61 and their attendant spacing ring 62.

The inner ball race-ring 55 has the V-shaped groove race 63 opposed to the V-shaped race 64 formed by adjacent chamfered inner edges of the ball race-rings 56 and 57, and said inner race-ring 55 is maintained rigid with the shaft 51 by the collars 65 and 66 which may be suitably keyed to the shaft 51 as by the set screws 67 and 68 respectively, or by other suitable means.

The outer race-ring 56 carries the spool or reel mounting 69 which conveniently serves as a housing for the ball bearing unit, having its annular inturned end flange 70 provided with the circular recess 71 arranged to clear the lateral face of the inner race-ring 55, and having an internally disposed recess 72 in its cylindrical wall 73 arranged to clear the external cylindrical surface of the outer race-ring 57 so as to permit relative axial movement of said race-ring 57 with respect to the race-rings 55 and 56 and the housing or mounting 69, being limited however by the bearing balls 61 traversing the opposed ball races in said race-rings.

The cylindrical wall 73 of the reel mounting 69 is internally threaded adjacent to its open or free side providing the screw threads 74 with which the adjustable annular closure flange 75 is threadedly engaged to be axially adjusted by means of a suitably provided tool which may engage the slots 76 in the outer face of said closure flange 75 to effect its rotation.

The closure flange 75 is provided with a circular pocket 77 in its inner surface arranged to retain the annular spring washer 79 which is preferably frustro-conoidal in form and which yieldingly bears against the ball race-ring 57 with pressure tending to force said race-ring 57 out of its normal plane of alignment with respect to its complementary cooperative inner ball race-ring 55, thus tending to effect such lateral pressure upon the bearing balls 61 as to produce abnormal rolling friction between said balls 61 and the relatively concentric race-rings 55, 56 and 57 respectively.

As in the assembly structure illustrated in Figs. 1 and 2, the friction produced between the bearing balls and their race-rings in this assembly structure may be varied by the axial adjustment of the closure flange 75 with respect to the reel mounting 69.

In the form of my invention illustrated in Fig. 4, the shaft or spindle 81 is provided with the bore 82 extending therethrough and carries the flanged ball bearing supporting collar 83 which may be suitably keyed to said shaft 81 to rotate therewith and upon which two ball bearing units are mounted, one comprising the relatively concentric inner and outer ball race-rings 85 and 86 respectively and the interposed bearing balls 87 with their attendant spacing ring 88; and the other comprising the inner and outer race-rings 89 and 90 respectively and the interposed bearing balls 91, with their attendant spacing ring 92.

The outer ball race-rings 86 and 90 are maintained relatively spaced apart by the annular spacing washer 93, and said outer race-ring 86 carries the spool or reel mounting 95 which has its inturned flange 96 provided with the circular recess 97 arranged to clear the lateral face of the inner race-ring 89 and which also has the annular removable and replaceable closure cap 99 threadedly engaged with the free end of the cylindrical wall 100 of said reel mounting 95 by the screw threads 101 and serving to retain the ball bearing units in the housing thus provided, and with the outer race-ring pocketed against the flange 96.

The inner race-ring 85 which is cooperative with the outer race-ring 86 to support the reel mounting 95, is rigidly carried by the collar 83 and pocketed against the flange 102 thereof. The collar 83 is provided with the circumferential recess 103 serving to clear the inner race-ring 89 and to thereby permit its relative axial movement.

Said collar 83 is further recessed adjacent to its unflanged end region 105 and provided with the external screw threads 106 with which the ball bearing friction adjusting nut 107 is threadedly engaged, and said nut 107 may preferably be provided with the annular projection 109 which bears upon the annular spring washer 110 whose outer peripheral region bears against the lateral face of the inner race-ring 89 and tends to yieldingly force said inner race-ring 89 toward the inner race-ring 85 and out of its normal plane of alignment with its cooperative outer race-ring 90.

Obviously, any inward adjustment of the nut 107 and consequent relative movement of the inner race-ring 89 and its cooperative outer race-ring 90 tends to frictionally bind the bearing balls 91 therebetween, which effects pressure through the spacing washer 93 tending to force the outer race-ring 86 out of its normal alignment with respect to its cooperative inner race-ring 85 and thereby cause said race-rings 85 and 86 to frictionally bind upon the bearing balls 87 and to thereby retard the rotation of the reel mounting 95, upon which the reel 112 may be conveniently attached and rotatably supported.

Although I have specifically described my invention as applicable to structures designed to support strand carrying spools or reels, it will be obvious that such means for restricting the rotation of ball bearings may be employed with equal facility for other purposes, and therefore I do not desire to limit my invention to the precise details of construction and arrangement as here-

in set forth as it is obvious that various modifications may be made therein without departing from the essential features of my invention as defined in the appended claims.

Having thus described my invention, I claim:

5. A ball bearing assemblage adapted to be mounted on a shaft and comprising a relatively rotatable housing, a ball bearing unit having its inner race-ring engaged with said shaft and its outer race-ring engaged in said housing, a ball bearing unit spaced from said first mentioned ball bearing unit and having its inner race-ring engaged with said shaft and having its outer race-ring floatingly spaced from the peripheral wall of said housing, and means adjustable to force the floating race-ring out of its normal registry with respect to its cooperative inner race ring, and thereby tending to cause the companion inner and outer race-rings to bind on the series of interposed spacing balls, whereby to retard the relative rotation of said shaft and housing.
10. A ball bearing assemblage adapted to be mounted on a shaft and comprising a relatively rotatable housing, a ball bearing unit having its inner race-ring engaged with said shaft and its outer race-ring engaged in said housing, a ball bearing unit spaced from said first mentioned ball bearing unit and having its inner race-ring engaged with said shaft and having its outer race-ring floatingly spaced from the peripheral wall of said housing, means adjustable to force the floating race-ring out of its normal registry with respect to its cooperative inner race-ring, and thereby tending to cause the companion inner and outer race-rings to bind on the series of interposed spacing balls, whereby to retard the relative rotation of said shaft and housing.
15. A ball bearing assemblage adapted to be mounted on a shaft and comprising a relatively rotatable housing, a ball bearing unit having its inner race-ring engaged with said shaft and its outer race-ring engaged in said housing, a ball bearing unit spaced from said first mentioned ball bearing unit and having its inner race-ring engaged with said shaft and having its outer race-ring floatingly spaced from the peripheral wall of said housing, means adjustable to force the floating race-ring out of its normal registry with respect to its cooperative inner race-ring, and thereby tending to cause the companion inner and outer race-rings to bind on the series of interposed spacing balls, whereby to retard the relative rotation of said shaft and housing.
20. A ball bearing assemblage adapted to be mounted on a shaft and comprising a relatively rotatable housing, a ball bearing unit having its inner race-ring engaged with said shaft and its outer race-ring engaged in said housing, a ball bearing unit spaced from said first mentioned ball bearing unit and having its inner race-ring engaged with said shaft and having its outer race-ring floatingly spaced from the peripheral wall of said housing, means adjustable to force the floating race-ring out of its normal registry with respect to its cooperative inner race-ring, and thereby tending to cause the companion inner and outer race-rings to bind on the series of interposed spacing balls, whereby to retard the relative rotation of said shaft and housing.
25. A ball bearing assemblage adapted to be mounted on a shaft and comprising a relatively rotatable housing, a ball bearing unit having its inner race-ring engaged with said shaft and its outer race-ring engaged in said housing, a ball bearing unit spaced from said first mentioned ball bearing unit and having its inner race-ring engaged with said shaft and having its outer race-ring floatingly spaced from the peripheral wall of said housing, means adjustable to force the floating race-ring out of its normal registry with respect to its cooperative inner race-ring, and thereby tending to cause the companion inner and outer race-rings to bind on the series of interposed spacing balls, whereby to retard the relative rotation of said shaft and housing.
30. A ball bearing assemblage adapted to be mounted on a shaft and comprising a relatively rotatable housing, a ball bearing unit having its inner race-ring engaged with said shaft and its outer race-ring engaged in said housing, a ball bearing unit spaced from said first mentioned ball bearing unit and having its inner race-ring engaged with said shaft and having its outer race-ring floatingly spaced from the peripheral wall of said housing, means adjustable to force the floating race-ring out of its normal registry with respect to its cooperative inner race-ring, and thereby tending to cause the companion inner and outer race-rings to bind on the series of interposed spacing balls, whereby to retard the relative rotation of said shaft and housing.
35. A ball bearing assemblage adapted to be mounted on a shaft and comprising a relatively rotatable housing, a ball bearing unit having its inner race-ring engaged with said shaft and its outer race-ring engaged in said housing, a ball bearing unit spaced from said first mentioned ball bearing unit and having its inner race-ring engaged with said shaft and having its outer race-ring floatingly spaced from the peripheral wall of said housing, means adjustable to force the floating race-ring out of its normal registry with respect to its cooperative inner race-ring, and thereby tending to cause the companion inner and outer race-rings to bind on the series of interposed spacing balls, whereby to retard the relative rotation of said shaft and housing.
40. A ball bearing assemblage adapted to be mounted on a shaft and comprising a relatively rotatable housing, a ball bearing unit having its inner race-ring engaged with said shaft and its outer race-ring engaged in said housing, a ball bearing unit spaced from said first mentioned ball bearing unit and having its inner race-ring engaged with said shaft and having its outer race-ring floatingly spaced from the peripheral wall of said housing, means adjustable to force the floating race-ring out of its normal registry with respect to its cooperative inner race-ring, and thereby tending to cause the companion inner and outer race-rings to bind on the series of interposed spacing balls, whereby to retard the relative rotation of said shaft and housing.

3. A ball bearing assembly adapted to be mounted on a shaft and comprising relatively spaced ball bearing units each having its inner race-ring engaged on said shaft, a mounting embracing said units and rigidly secured to the outer race-ring of one of said units but free from the other unit, and means axially adjustable on said mounting arranged to axially force the inner and outer race-rings out of normal relative registry.
45. A ball bearing assembly adapted to be mounted on a shaft and comprising relatively spaced ball bearing units each having its inner race-ring engaged on said shaft, a mounting embracing said units and rigidly secured to the outer race-ring of one of said units but free from the other unit, and means axially adjustable on said mounting arranged to axially force the inner and outer race-rings out of normal relative registry.
50. A ball bearing assembly comprising a shaft, relatively spaced ball bearing units each having its inner race-ring engaged on said shaft, a spacer interposed between said inner race-rings, a mounting embracing said units and carried by the outer race-ring of one of said units but spaced free from contact with the other unit, an adjustable follower threadedly engaged with said mounting arranged to axially force the inner and outer race-rings out of their normal registry, and yielding means interposed between the free outer race-ring and said follower.

55. A ball bearing assembly comprising a shaft having relatively spaced ball bearing units each having its inner race-ring encircling said shaft, a spacer interposed between one of the race-rings of each of the respective units, a mounting rotatably carried by said units and having transverse and circumferential depressions in its peripheral surface varying in depth between said transverse depressions, means adjustable to force the race-rings of the respective units axially out of their normal alignment, and a reel detachably carried by said mounting and having projections
60. A ball bearing assembly comprising a shaft having relatively spaced ball bearing units each having its inner race-ring encircling said shaft, a spacer interposed between one of the race-rings of each of the respective units, a mounting rotatably carried by said units and having transverse and circumferential depressions in its peripheral surface varying in depth between said transverse depressions, means adjustable to force the race-rings of the respective units axially out of their normal alignment, and a reel detachably carried by said mounting and having projections
65. A ball bearing assembly comprising a shaft having relatively spaced ball bearing units each having its inner race-ring encircling said shaft, a spacer interposed between one of the race-rings of each of the respective units, a mounting rotatably carried by said units and having transverse and circumferential depressions in its peripheral surface varying in depth between said transverse depressions, means adjustable to force the race-rings of the respective units axially out of their normal alignment, and a reel detachably carried by said mounting and having projections
70. A ball bearing assembly comprising a shaft having relatively spaced ball bearing units each having its inner race-ring encircling said shaft, a spacer interposed between one of the race-rings of each of the respective units, a mounting rotatably carried by said units and having transverse and circumferential depressions in its peripheral surface varying in depth between said transverse depressions, means adjustable to force the race-rings of the respective units axially out of their normal alignment, and a reel detachably carried by said mounting and having projections
75. A ball bearing assembly comprising a shaft having relatively spaced ball bearing units each having its inner race-ring encircling said shaft, a spacer interposed between one of the race-rings of each of the respective units, a mounting rotatably carried by said units and having transverse and circumferential depressions in its peripheral surface varying in depth between said transverse depressions, means adjustable to force the race-rings of the respective units axially out of their normal alignment, and a reel detachably carried by said mounting and having projections

guided by said depressions into engagement with the floor of the circumferential depression at the region of lesser depth.

6. A ball bearing assembly comprising a shaft collar having a radially extending flange, a ball bearing unit having its inner race-ring mounted on said collar with its inner race-ring engaged with said flange, a relatively rotatable mounting carried by the outer race-ring of said unit, a second ball bearing unit having its outer race-ring engaged in said mounting in spaced relation to the first mentioned outer race-ring, and

5 having its inner race-ring encircling said collar but circumferentially spaced therefrom, an adjusting nut in threaded engagement with said collar arranged for relative axial movement with respect thereto, and a yielding washer interposed between said nut and the second mentioned inner race-ring tending to yieldingly force said inner race rings toward each other and out of their normal axial plane of alignment with their 10 respective cooperative outer race rings.

JOSEPH GECZY.
